DESIGN FOR A RADIO RECEIVER CABINET

Alexis De Sakhnoffsky, Philadelphia, Pa., assignor to Muzak Corporation of Ohio, Lakewood, Ohio, a corporation of Ohio

Application August 10, 1935, Serial No. 58,061

Term of patent 14 years

To all whom it may concern:

Be it known that I, Alexis de Sakhnoffsky, a subject of the Czarist regime of Russia, residing at Philadelphia, in the county of Philadelphia and State of Pennsylvania, have invented a new original, and ornamental Design for Radio Receiver Cabinet, of which the following is a specification, reference being had to the accompanying drawing, forming part thereof.

The drawing is a perspective view of a radio receiver cabinet embodying my design.

The design resides in the configuration of the cabinet in combination with a centrally disposed tuning dial and grill positioned thereunder in the forward part of the cabinet, as shown in the drawing. Only a portion of the grill ornamentation is shown, it being understood that the entire grill is of a similar appearance.

I claim:

The ornamental design for radio receiver cabinet as shown and described.

ALEXIS DE SAKHNOFFSKY.
